UNITED STATES PATENT OFFICE.

LEWIS R. TOMPKINS, OF ATLANTIC CITY, NEW JERSEY, ASSIGNOR OF ONE-HALF TO
GEORGE H. SHEA, OF QUARRYVILLE, PENNSYLVANIA.

ROPE CLAMP.

Application filed February 5, 1925. Serial No. 7,173.

To all whom it may concern:

Be it known that I, LEWIS R. TOMPKINS, a citizen of the United States, residing at Atlantic City, in the county of Atlantic and State of New Jersey, have invented certain new and useful Improvements in Rope Clamps, of which the following is a specification.

This invention relates to rope clamps and more particularly to such a device adapted for use with clothes line poles or props for maintaining the clothes line in proper position.

An important object of the invention is to provide a device of the above mentioned character having a clamping element adapted to engage the rope or line within the notch usually provided in the upper end of a clothes line prop for maintaining the line in position.

A further object of the invention is to provide a simple construction which is adapted for attachment to a clothes line prop and having a clamping element which is adapted to be conveniently moved downwardly into engagement with the clothes line, means being provided for engaging the clamping member for maintaining it in clamping position.

Other objects and advantages of the invention will be apparent during the course of the following description.

In the drawings I have shown one embodiment of the invention. In this showing,

Figure 1 is a side elevation of a clothes line prop showing the device applied,

Figure 2 is a side elevation taken at right angles to Figure 1, parts being shown in section,

Figure 3 is a plan view, and,

Figure 4 is a detail perspective of the bracket and cam.

Referring to the drawings, the numeral 10 designates an ordinary clothes line prop usually formed rectangular in cross section as shown and provided in its upper end with a V-shaped notch 11 adapted to receive a line 12 therewithin.

Referring to Figures 2 and 4, the numeral 13 designates a plate provided with apertures 14 for receiving screws 15 whereby the plate may be secured against the side of the prop near its upper end. The plate 13 is provided with a reduced portion 16 which

projects beyond the edge of the prop as shown in Figures 2 and 3. A substantially U-shaped bracket 17 is arranged against the reduced portion 16 as shown in Figure 4. The base portion 18 of the bracket is preferably arranged against the edge of the prop while one of the arms 19 of the bracket is secured by rivets 20 or the like to the extension 16. The arms 19 and extensions 16 are provided with alined openings 21 for a purpose to be described. A bar 22 is connected between the arms of the bracket and is rigidly secured thereto.

Referring to Figure 2, the numeral 23 designates a line engaging member preferably formed of flat metal as shown. The body portion of the member 23 is preferably substantially parallel to the bar 22 to be engaged thereby and the upper end of the member 23 is bent as at 24 to pass over the end of the prop. The member 23 is further provided near its upper end with a depending portion 25 terminating in an engaging end 26 twisted at right angles thereto and provided with a cut-out end 27 adapted to engage the line 12 as shown. The lower end 28 of the member 23 is turned outwardly as at 29 to provide a finger piece or handle.

A cam 29 is arranged between the arms 19 of the bracket 17. The cam is provided with eccentric pins 30 at its ends adapted to be journaled in the openings 21. The cam is provided with an operating handle 31 extending outwardly and downwardly therefrom.

The operation of the device is as follows:

One of the arms 19 of the bracket is riveted as at 20 to the extension 16 whereupon the bar 22 and cam 29 are arranged in position. The other arm 19 of the bracket is then bent inwardly so that the outer pin 30 is arranged in the opening 21 thereof. The ends of the bar 22 then may be removed to maintain the arms 19 in parallel relation to prevent the cam 29 from becoming displaced. The engaging member 23 may be inserted in position by raising the handle 31 and inserting the lower end between the bar 22 and cam 29. With the line in position as shown in Figure 2, the finger piece 28 may be depressed by the operator to bring the end 26 of the member 23 into firm engagement with the line. The handle 31 is then moved downwardly swinging

the cam 29 about the pins 30 until the cam firmly engages the member 23 to prevent it from moving upwardly. It will be apparent that any tendency of the member 23 to move upwardly will revolve the cam 29 whereby it will more firmly engage the holding member to prevent upward movement thereof. The provision of the plate 13 allows the device to be easily applied to a clothes line prop 10 since the screws for securing it in position will be readily accessible from the side of the prop.

It is to be understood that the form of my invention herewith shown and described is to be taken as a preferred example of the same and that various changes in the shape, size, and arrangement of parts may be resorted to without departing from the spirit of the invention or the scope of the subjoined 20 claims.

I claim:

1. A device of the character described comprising a clothes line prop having a notch in its upper end for supporting a line, a manually movable member arranged adjacent one side of said prop and having its upper end turned to extend downwardly into said notch to engage said line, a stationary element arranged against one side of said member, and a cam carried by said prop and adapted to bind said member between said cam and said stationary element.

2. A device of the character described comprising a clothes line prop having a notch in its upper end for supporting a line, a bracket secured against one side of said prop, a member having a portion arranged substantially parallel to said prop, and extending through said bracket, a portion of said bracket contacting with one side of said member, said member having its upper end turned to extend downwardly into said notch to engage the line, and clamping means carried by said bracket and adapted to bind

said member between said clamping means 45 and said bracket portion.

3. A device of the character described comprising a clothes line prop having a notch in its upper end for supporting a line, a plate secured to one side of said prop, a substantially U-shaped bracket carried by said plate and having its base portion arranged against another side of the prop, a member arranged adjacent said prop and extending through said bracket, one side of 55 said member being adapted to contact with a portion of said bracket, said member having its upper end turned to extend downwardly into such notch to engage the line, and a cam mounted between the arms of said 60 bracket and adapted to bind said member between said clamping means and said bracket portion.

4. A device of the character described comprising a clothes line prop having a notch in its upper end for supporting the line, a plate secured to one side of said prop, a substantially U-shaped bracket carried by said plate and having its base portion arranged against another side of the prop, a 70 bar connected between the arms of said bracket near the base portion thereof, a cam rotatably mounted between the arms of said bracket substantially parallel to said bar, a member arranged substantially parallel 75 to the prop and extending between said bar and said cam, said member having its upper end turned to extend downwardly into said notch to engage the line, said cam being rotatable to grip said member between 80 its inner face and said bar to prevent disengagement of the end of said member from the line, said member having its lower end turned outwardly to provide an operating handle.

In testimony whereof I affix my signature.

LEWIS R. TOMPKINS.
